United States Patent Office

Des. 185,196
Patented May 19, 1959

185,196

GIRDLE

Joan G. Gant, Dover, Del., assignor to International Latex Corporation, Dover, Del., a corporation of Delaware

Application May 2, 1958, Serial No. 50,721

Term of patent 14 years

(Cl. D20—2)

Fig. 1.

Fig. 2.

The dominant feature of the design resides in the portion shown in full lines on the drawings.

I claim:

The ornamental design for a girdle, substantially as shown and described.
